UNITED STATES PATENT OFFICE

95,810

DESIGN FOR A VEHICLE LAMP GLOBE OR SIMILAR ARTICLE

Harold B. Donley, Columbus, Ohio, assignor to
Columbus Metal Products Inc., Columbus,
Ohio, a corporation of Ohio

Application April 1, 1935, Serial No. 56,146

Term of patent 7 years

To all whom it may concern:

Be it known that I, Harold B. Donley, a citizen
of the United States, residing at Columbus, in the
county of Franklin and State of Ohio, have in-
vented a new, original, and ornamental Design
for Vehicle Lamp Globe or Similar Article, of
which the following is a specification, reference
being had to the accompanying drawing, forming
a part thereof.

Fig. 1 is a perspective view of a vehicle lamp
globe or similar article showing my new design;

Fig. 2 is a top plan view thereof;
Fig. 3 is a side elevation;
Fig. 4 is a horizontal sectional view on the
plane indicated by the line IV—IV of Fig. 3;
Fig. 5 is a similar view on the line V—V of
Fig. 3.

I claim:
The ornamental design for a vehicle lamp
globe or similar article, as shown.

HAROLD B. DONLEY.
